(57) **CLAIM**

The ornamental design for a display screen or portion thereof with graphical user interface, as shown and described.

DESCRIPTION

The FIGURE is a front view of a display screen or portion thereof with graphical user interface, showing the new design.

The broken line showing of the display screen, indicia, and other portions of the graphical user interface form no part of the claimed design.

In the FIGURE, the dotted lines of the first two long vertical bars from the left are part of the claimed design.

1 Claim, 1 Drawing Sheet
